INVENTOR

UNITED STATES PATENT OFFICE

113,592

DESIGN FOR A BEDSPREAD

Augusta K. Bartholomew, New York, N. Y., assignor to Harriette A. Lawson, Signal Mountain, Tenn.

Application January 25, 1939, Serial No. 82,601

Term of patent 3½ years

To whom it may concern:

Be it known that I, Augusta K. Bartholomew, a citizen of the United States, residing at New York city, county of New York, and State of New York, have invented a new, original, and ornamental Design for Bedspreads, of which the following is a specification, reference being had to the accompanying drawing, forming part thereof,

The figure of the drawing is a plan view of a bedspread showing my design.

I claim:

The ornamental design for a bedspread substantially as shown.

AUGUSTA K. BARTHOLOMEW.
